CLAIM

The ornamental design for a table lamp as shown and described.

DESCRIPTION

FIG. 1 is a bottom perspective view of a table lamp showing my new design;

FIG. 2 is a top perspective view thereof;

FIG. 3 is left elevational view thereof;

FIG. 4 is right elevational view thereof;

FIG. 5 is a front elevational view thereof;

FIG. 6 is a rear elevational view thereof;

FIG. 7 is a top plan view thereof; and,

FIG. 8 is a bottom plan view thereof.

The evenly broken lines illustrate portions of the table lamp that form no part of the claimed design.
